UNITED STATES PATENT OFFICE

JOHN B. GLASS, OF GRAND ISLAND, NEBRASKA

CHAIR

Application filed March 12, 1929. Serial No. 346,378.

The present invention relates to a chair and has for its prime object to provide a structure whereby the chair may be mounted to swing or may be held in a stationary position.

Another very important object of the invention resides in the provision of a chair of this nature which is exceedingly simple in its construction, strong and durable, inexpensive to manufacture, compact and convenient in its arrangement of parts, not likely to easily become out of order, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a side elevation of the chair embodying the features of my invention,

Figure 2 is a front elevation thereof,

Figure 3 is a top plan view thereof,

Figure 4 is an enlarged detail section taken substantially on the line 4—4 of Figure 1,

Figure 5 is a perspective view of the catch for holding the chair stationary,

Figure 6 is a perspective view of one of the swinging arms for supporting the chair,

Figure 7 is an enlarged detail front elevation of one of the front standards showing the upper portion thereof with the bracket welded thereto,

Figure 8 is a detail section taken substantially on the line 8—8 of Figure 7,

Figure 9 is a detail section taken substantially on the line 9—9 of Figure 7,

Figure 10 is an enlarged fragmentary detail view of the upper portion of the front supporting structure showing a coil spring associated with the swinging arm,

Figure 11 is a front elevation thereof,

Figure 12 is a detail perspective view showing the coil spring welded to the arm,

Figure 13 is an enlarged detail elevation of the upper portion of the front supporting structure showing another embodiment of the spring mount for the swinging arm, and

Figure 14 is a perspective view of one end of one of the arms.

Referring to the drawing in detail, it will be seen that numeral 5 denotes a pair of front uprights or legs which converge upwardly toward each other and are connected by cross members 6 and 7. Numerals 8 denote a pair of rear uprights or legs which converge upwardly toward each other and are connected together by cross pieces 9 and 10.

The uprights 5 and uprights 8 lean upwardly toward each other as is indicated to advantage in Figure 1. In the first embodiment of the invention disclosed to advantage in Figures 1 to 9 inclusive it will be seen that inverted U-shaped brackets 11 are welded to the upper portions of the uprights 5 and have pivoted between their extremities arms 12 intermediately provided with depending extensions 14 to which a step or foot rest 15 is secured.

The rear ends of the arms 12 are twisted as is indicated at 16 and secured to the seat 17 provided with side arms 18, a back structure 19, a tray 20 restable on the arms 18 and supported by rods 21 pivoted as at 22 to the back structure 19.

A keeper 23 is mounted at the rear end of the seat 17 to be engaged by a book arm 24 hingedly mounted as at 25 on the cross member 9 for the purpose of holding the shaft stationary.

Rearwardly curved arms or brackets 27 are secured to the upper ends of the uprights 5 and at their rear ends have secured springs 28 which are adjustably secured as at 29 with the platform, foot rest or step 15. Springs 30 are anchored to the rear portion of the seat 17 and to bolts 31 which are adjustably connected as at 32 with the cross member 10.

The legs 5 and 8 are connected by longitudinal braces 33 and 34. A basket 35 is mounted between the lower braces 34 by having hooks 36 engaged with said braces. The braces 33 and 34 are welded to the uprights 5 as is indicated to advantage in Figure 4.

From the above detailed description, it will be seen that springs 28 tend to hold the seat 17 in a substantial horizontal position in cooperation with the springs 30 thereby

resiliently mounting the seat so that the same will rock under ordinary conditions in actual use.

When it is desired to hold the chair rigid then the hook arm 24 may be engaged in the keeper 23. In Figure 10 it will be seen that the brackets 11' have arms 12' pivoted thereto and coil springs 40 are secured to the arms 12' as is shown to advantage in Figure 12 10 and are secured by welding as is indicated at 41 to the uprights 5'.

In Figures 14 and 15 it will be seen that arms 12^a are pivoted in brackets 11^a welded to uprights 5^a and arcuate depending extensions 14^a have reduced ends 42 welded in springs 43 which are welded to the uprights 5^a. The function of springs 40 and 43, of course are the same as the function of the springs 28.

It is thought that the construction, operation, utility and advantages of the invention will now be quite apparent to those skilled in this art without a more detailed description thereof.

The present embodiments of the invention have been disclosed in considerable detail merely for the purposes of exemplification since in actual practice they attain the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. A structure of the class described comprising a frame, inverted U-shaped brackets secured in the frame, arms pivotally engaged between the extremities of the brackets, depending extensions on intermediate portions of the arms, a foot rest between the extensions, brackets mounted on the frame above the arms, springs engaged with the last mentioned brackets and with the foot rest.

2. A structure of the class described comprising a frame, inverted U-shaped brackets secured in the frame, arms pivotally engaged between the extremities of the brackets, depending extensions on intermediate portions of the arms, a foot rest between the extensions, brackets mounted on the frame above the arms, springs engaged with the last mentioned brackets and with the foot rest, adjustable means for securing the springs to the foot rest.

3. A structure of the class described comprising a frame, inverted U-shaped brackets secured in the frame, arms pivotally engaged between the extremities of the brackets, depending extensions on intermediate portions of the arms, a foot rest between the extensions, brackets mounted on the frame above

the arms, springs engaged with the last mentioned brackets and with the foot rest, adjustable means for securing the springs to the foot rest, springs secured to the seat and extending downwardly therefrom and adjustably anchored to the frame.

4. A structure of the class described comprising a frame, inverted U-shaped brackets secured in the frame, arms pivotally engaged between the extremities of the brackets, depending extensions on intermediate portions of the arms, a foot rest between the extensions, brackets mounted on the frame above the arms, springs engaged with the last mentioned brackets and with the foot rest, adjustable means for securing the springs to the foot rest, springs secured to the seat and extending downwardly therefrom and adjustably anchored to the frame, a pivotally mounted hook on the frame, a keeper on the seat with which the hook may be engaged.

5. A structure of the class described comprising a pair of front uprights, a pair of rear uprights, braces between the uprights, a pair of arms, means for pivotally mounting the arms to upper portions of the front uprights to extend rearwardly therefrom, a seat on the rear ends of the arms, spring means urging the seat downwardly, said arms having depending extensions, a foot rest between the extensions, rearwardly curved brackets on the upper ends of the front uprights, springs engaged with said brackets and adjustably engaged with said foot rest.

In testimony whereof I affix my signature.

JOHN B. GLASS.
